(57) **CLAIM**

We claim the ornamental design for a box enclosure for a camera, as shown and described.

DESCRIPTION

FIG. 1 is a perspective view of a box enclosure for a camera; FIG. 2 is a front elevation view of the box enclosure for a camera;

FIG. 3 is a back elevation view of the box enclosure for a camera;

FIG. 4 is a left side elevation view of the box enclosure for a camera, the right side elevation view being a mirror image of the left side elevation view;

FIG. 5 is a top plan view of the box enclosure for a camera; and,

FIG. 6 is a bottom plan view of the box enclosure.

The broken lines depict portions of a box enclosure for a camera in which the design is embodied that form no part of the claimed design.
